MACHINE FOR MAKING BOOK COVERS

Fred Humphrey and Adam Krieger, Denver, Colo.,
assignors to The Pass Book and Check Cover
Company, Denver, Colo.

Application June 14, 1937, Serial No. 148,140

12 Claims. (Cl. 11—2)

This invention relates to improvements in automatic book-binding machinery and has reference more particularly to a machine for making covers for bank pass books.

5 Bank pass book covers are provided with rectangular cardboards on each side to stiffen them and these are covered with leather, cloth or similar material glued to the cardboards and which forms the outer finished surface of the book. The 10 leather or cloth covering connects the two sides and forms the hinge. The leather or cloth cover or jacket is cut of such size that it can be folded over the outer edges and the ends of the cardboards so as to produce a finished appearance. 15 In assembling the jacket and the cardboards to form the cover, one side of the jacket is covered with glue and the cardboards are then placed on the glued surface in such a position as to leave the right amount of margin to permit the jacket 20 to be turned over the edges of the cardboards and far enough apart to provide the necessary hinge.

It is an object of this invention to produce a machine that will place the stiffening cardboards onto the freshly glued cover or jacket, accurately as to position, and to do this quickly and automatically.

Another object of this invention is to produce a machine that will automatically assemble the 10 cover parts and deliver them to a conveyor.

A further object is to produce a machine of such design that the freshly glued jackets can be readily positioned against suitable stops and retained in such position until the stiffening cardboards have been applied.

A still further object is to produce a machine that can be used for assembling covers of different sizes.

Another object is to produce a machine for the purpose specified, that will operate quietly and which shall be simple and inexpensive.

The above and other objects that may become apparent as the description proceeds are attained by means of a combination and arrangement of parts that will now be described in detail and reference for this purpose will be had to the accompanying drawings in which the machine has been illustrated in its preferred form and in which

Figure 1 is a side elevation of the improved book binding machine;

Figure 2 is a general plan view thereof;

Figure 3 is a fragmentary section to an enlarged scale, taken along line 3—3, Figure 1;

Figure 4 is a fragmentary section to an enlarged scale, taken along line 4—4, Figure 1;

Figure 5 is a fragmentary section to an enlarged scale, taken along line 5—5, Figure 4, with the carriage just about to strip a card from the magazine, shown thus for clarity; and

Figure 6 is a plan view of the carriage, showing certain details of the construction.

In the drawings reference character 7 denotes, as a whole, the frame that supports the various 10 elements of the machine, 8 is the main driven pulley and 9 a belt delivering power from any source, not shown. The shaft 10 on which pulley 8 is non-rotatably mounted, carries cams 12 and 13 and rotates them in the direction indicated by 15 the arrow, and is journaled in bearings 14.

Cam 12 bears against rocking beam 15 which is journaled for oscillation about pivot 16, and is held in following contact with cam 12 by springs 17. The upper end of the beam is provided with 20 a clevis 18 to which is attached one end of a cord or belt 19 that passes over pulleys 20 and 21 on the frame 7 and back over pulley 22 on the beam and is anchored to the latter at 24, by means of spring 23, Figure 3.

Elevated supports 25 hold card magazines 26 above a reciprocating conveyor or carriage 27, which slides in grooves 35. Carriage 27 is attached by means of an arm 28 and clamps 29 to cord 19. Carriage 27 carries a plate 30 on which 30 are mounted stripper lugs 31, and a guide block 32, which are adjustable as to their exact location, by means of slots and screws as shown at 33 and 34 respectively, in Figure 6. Plate 30 is also adjustable on carriage 27 by similar means 36.

The cardboard magazines 26 each comprise a housing 37, two vertical guides 38, horizontal guide flanges 39 and a delivery clip 40. At the lower end of clip 40 a tongue 41 is bent outwardly and upwardly and a pair of tongues 42 40 are bent inwardly. Cardboards 43, to be used in the book covers, are stacked in the magazine and rest on flanges 44 at their sides and on tongues 42 at one end.

The ends of each magazine or housing 37 45 are each provided with a cleat 37a, secured in place by rivets, or spot welding, and serve to support the magazines from the upper edges of members 25 (see Figure 5).

The feed clip 40 is supported from the upper 50 edge of the front wall of the magazine by a bent over tip 45 to the outer surface of which a boss 46 is attached. A slide 47 (Figure 4) has each end provided with a downwardly extending tongue 47a which slides in the space between the 55

bars 25 and 25a and with similar offset tongues 47b. The upper edge of slide 47 is provided with two inclined cam surfaces 48 that engage the bosses 46, when the slide is moved towards the right so as to hold the feed clips in elevated and inoperative position.

Cam 13, Figure 1, engages an arm 49 attached to lever 50, which is pivoted at 51 and has a U clip 52 at its upper end. The clip engages the bent-down end 53 of shaft 54, that is journaled in brackets 55 and to which the arms 56 are rigidly attached. A cross bar 57 connects the other ends of arms 56 and carries screws 58 which are pointed on their lower ends.

15 A curved finger 59 is attached to bar 57 and its end is bent downwardly and pointed. A resilient rider 60 is attached to one end of bar 57 and extends downwardly slightly farther than the points of screws 58, and finger 59.

20 A pulley 61 is carried by the main shaft 10 and drives a crossed belt 62 to rotate conveyor roller 63 in the opposite direction so that conveyor belts 64 will carry the book covers away from the machine in the direction indicated by the 25 arrow.

25 In operation the carriage 27 reciprocates, passing under the cardboard magazines in opposite directions at each cycle and is driven by the cord 19 and beam 15 as this is acted upon by 30 cam 12. The spring anchorage 23, of the cord permits it to change length slightly at each stroke and the particular shape of the cam 12 causes the carriage to stop for a short period of time at each end of its path.

35 The operator thus has time to place a freshly glue-coated jacket on the carriage plate 30, against the stripper lugs 31 and guide block 32 as shown in dotted lines at 65, Figure 6. As the carriage passes beneath the magazines the stripper lugs remove the lower cardboard 43a from 40 each magazine and force it through opening 66 underneath the flange 39 and down onto the glued upper surface of the jacket.

45 Only the lowermost board projects down below the tongue 41 which is raised slightly by the lug 31 as it passes below it, bringing the lowest board into place to be stripped from the magazine. Two boards, one from each magazine, are thus placed on each jacket as shown in dotted 50 lines at 65a and 43b in Figure 2, at each forward stroke of the carriage. The boards are directed down onto the jacket through and by slots 66.

55 When the carriage reaches the extreme left hand end of its reciprocating cycle, cam 13 functions to permit the arm 49 to drop slightly thereby permitting lever 50 to move clockwise whereby upon arms 56 drop and place the points of screws 58 and finger 59 onto the semi-finished cover assembly. The rider 60 contacts the carriage plate 30 to prevent the points from passing entirely through the boards. Points 58 together with the finger 59, which falls on the jacket, between the cardboards, hold the work stationary as the carriage returns toward the right. As the 60 carriage is moved from under the cover, it falls onto conveyor belts 64 to be taken away to the next operation.

65 The lugs 31 and guide 32 as well as plate 30 can be adjusted for various sizes of boards and jackets, and by raising the clips 40 out of range of the stripper lugs by means of slide 47, the operator can stop the machine from delivering cardboards.

70 It will be seen from the above that by means 75 of the simple mechanism described and shown

in the drawings, the operator merely feeds the glued jackets onto the reciprocating conveyor or table whenever it returns to its extreme right hand position and the machine will then strip one cardboard from each magazine and deposit it in a predetermined position thereon. The jackets with the cardboards attached thereto are then deposited on the conveyor belts and transferred to a station where another operator turns the edges of the jacket about the edges of the 10 cardboards so as to finish the covers.

Having described the invention, what is claimed as new is:

1. In a cover making machine, a carrier element mounted for reciprocatory movement, means for reciprocating the carrier element, a relatively stationary magazine positioned above the carrier element, means for releasably supporting a stack of boards in the magazine, a positioning lug and a stripper lug secured to the carrier element, for 15 positioning a sheet of cover material thereon, the stripper lug forming a means cooperatively related to the board supporting means of the magazine, for removing the lowermost board from the stack and depositing it in a predetermined position on the sheet of cover material when the carrier element moves in one direction, and means for removing the assembly of board and cover material from the carrier element when it moves 20 in the other direction.

2. In a cover making machine, a movable carrier element, a board magazine positioned above the carrier element, guide lugs on the carrier located to position a sheet of cover material thereon, a stripper lug positioned on the carrier element to pass beneath the magazine, means for releasably supporting a stack of boards in the magazine, means comprising a portion of the board supporting means, and the stripper lug for removing the lowermost board from the stack and 25 depositing it in a predetermined position on the cover sheet as the latter is moved beneath the magazine, and the mechanism for moving the carrier element with reference to the magazine in the direction of discharge of boards therefrom.

3. In a cover making machine, a movable carrier element, a magazine positioned above the carrier element, mechanism for moving the carrier element with reference to the magazine in the direction of discharge of boards therefrom, 30 stripper and guide lugs on the carrier, located to position a sheet of cover material thereon, the stripper lug being positioned to pass beneath the magazine, means for releasably supporting a stack of boards in the magazine, means comprising a portion of the board supporting means, and the stripper lug for removing the lowermost board from the stack and depositing it in a predetermined position on the cover sheet as the latter is 35 moved beneath the magazine, and means for removing the assembly of cover sheet and board from the carrier element after the board has been positioned thereon.

4. In a machine of the class described, a carrier element, a magazine positioned above the same, mechanism for moving the carrier element with reference to the magazine in the direction of discharge of boards therefrom, stripper and guide lugs on the carrier element and positioned to 40 properly locate a sheet of cover material thereon, the stripper and guide lugs being positioned to pass the sheet beneath the magazine, means for supporting a stack of boards in the magazine, a portion of said supporting means being vertically 45

- movable and provided with spaced rearwardly extending tongues that engage underneath the front ends of the boards, means engageable by the stripper lug for raising the movable supporting 5 means, the stripper lug having means for engaging the front edge of the bottom board of the stack, for removing and placing a board in a predetermined position on the sheet of cover material.
10. 5. A cover making machine comprising a frame, a shaft rotatably mounted thereon, a carrier element, means for supporting the carrier element for reciprocation, means operated by the rotation of the shaft for reciprocating the carrier element, 15 a board magazine supported by the frame, above the carrier element, means carried by the magazine for removably supporting a stack of boards, said means comprising inturned flanges on the sides of the magazine and a vertically movable member engaging underneath the front end of the stack of boards, a guide lug and a stripper lug on the carrier element, said lugs serving to position a sheet of adhesive-coated cover material thereon, the stripper lug comprising means operatively- 20 related to the vertically movable member for raising the latter and for removing the lowermost board from the stack and for depositing it in a predetermined position on the cover sheet as the latter is moved underneath the magazine, and 25 means operated by the rotation of the shaft for engaging the assembly of cover sheet and board and effecting its removal from the carrier.
6. A cover making machine comprising a frame, a shaft rotatably mounted thereon, a carrier element, means for supporting the carrier element for reciprocation, means operated by the rotation of the shaft for reciprocating the carrier element, a magazine supported by the frame, above the carrier element, means carried by the magazine 30 for removably supporting a stack of boards, said means comprising inturned flanges on the sides of the magazine and a vertically movable member engaging underneath the front end of the stack of boards, a guide lug and a stripper lug on the carrier element, said lugs serving to position a sheet of adhesive-coated material thereon, the stripper lug comprising means operatively related to the vertically movable member for raising the latter and for removing the lowermost board from the 35 stack and for depositing it in a predetermined position on the adhesive-coated material as the latter is moved underneath the magazine, means operated by the rotation of the shaft for engaging the assembly of material and board and effecting 40 its removal therefrom, and a conveyor positioned to receive the cover assembly as it is removed from the carrier element.
55. 7. In a book-cover making machine, the combination with a carriage movably mounted for the conveyance of book-cover parts, and a magazine positioned above said carriage for the deposit of other book-cover parts onto the first mentioned parts, the carriage having means for stripping book-cover parts from said magazine, of mechanism for reciprocating the carriage, comprising, a rotary cam, an oscillatory arm in following relation thereto, and a flexible element connecting the arm with the carriage.
8. In a book-cover making machine, the combination with a carriage movably mounted for the conveyance of book-cover parts, and a magazine positioned above said carriage for the deposit of other book-cover parts onto the first mentioned parts, the carriage having means for stripping book-cover parts from said magazine, of mechanism for reciprocating the carriage, comprising, a 5 rotary cam, an oscillatory arm in following relation thereto, a flexible element connecting the arm with the carriage, and synchronized mechanism for automatically removing cover parts from the carriage.
10. 9. In a book-cover making machine, the combination with a carriage movably mounted for the conveyance of book-cover parts, and a magazine positioned above said carriage for the deposit of other book-cover parts onto the first mentioned parts, the carriage having means for stripping book-cover parts from said magazine, of mechanism for reciprocating the carriage, comprising, a non-symmetrical rotary cam, an oscillatory arm in following relation thereto, and a flexible element connecting the arm with the carriage.
15. 10. In a book-cover making machine, the combination with a carriage movably mounted for the conveyance of book-cover parts, and a magazine positioned above said carriage for the deposit of other book-cover parts onto the first mentioned parts, the carriage having means for stripping book-cover parts from said magazine, of mechanism for reciprocating the carriage, comprising, a 20 rotary cam, an oscillatory arm in following relation thereto, a flexible element connecting the arm with the carriage, and synchronized mechanism for automatically engaging and removing cover parts from the carriage at a predetermined position of said carriage in its reciprocal cycle.
25. 11. In a cover making machine, a movable carrier element, a magazine positioned above the same and provided with means for releasably supporting a stack of boards for deposit onto the carriage element, means on the carrier element 30 positioned and adapted to contact and remove the bottom board from the stack as the carrier element moves beneath the same, and mechanism effective for moving said carrier element with reference to the magazine, in the direction of discharge of the boards thereonto.
35. 12. In a cover making machine, a carrier element, a magazine positioned above the carrier element, means for releasably supporting a stack of boards in the magazine, a stripper secured to 35 the carrier element in cooperative spaced relation with the board supporting means, effective for contacting and moving the lowermost board from the stack when the carriage moves therebelow, and depositing said board in a predetermined 40 position on the carrier element, mechanism for removing the carrier element with reference to the magazine, in the direction of discharge of the boards therefrom, and means for removing the boards from the carrier element.

FRED HUMPHREY.
